UNITED STATES PATENT OFFICE

KOLOMAN REZSNY, OF BUDAPEST, HUNGARY, ASSIGNOR TO THE FIRM HYDROMETER
A.-G., OF BRESLAU

SPEEDOMETER

Application filed August 9, 1929, Serial No. 384,762, and in Germany August 13, 1928.

My invention relates to improvements in positively driven speedometers and more particularly to positively driven speedometers for locomotives and the like.

5 It is an object of the invention to procure a speedometer of the kind described above, which is of simple construction and which is reliable in operation.

10 Another object of the invention is to improve the construction of the measuring and setting parts of speedometers.

15 A further object of the invention is to procure a device for the automatic winding up of speedometer clockworks.

20 Still further objects of the invention are to procure novel and advantageous devices for recording the time indications and the direction of driving on the recording strips of a speedometer.

25 A constructional form of my invention is shown by way of an example in the accompanying drawings, in which

Fig. 1 is an elevation of the entire speedometer device with a wall of the casing removed.

30 Fig. 2 is a section on the line II—II of Fig. 1,

Fig. 3 is a sectional view of the clockwork.

35 Fig. 4 shows a detail of the clockwork on an enlarged scale.

Fig. 5 shows the recording strip.

40 Fig. 6 shows the driving means of the device for recording the direction of driving.

45 Fig. 7 is a partial section on the line VII—VII of Fig. 6,

Fig. 8 is a section on the line VIII—VIII of Fig. 6,

50 Fig. 9 is a section on the line IX—IX of Fig. 6.

In the casing A of a speedometer is mounted the vertical driving spindle 2 which is driven for instance from a locomotive wheel by means of a suitable gear. On the said driving spindle is arranged a sleeve 1 with a worm 3 which is always driven in one direction for instance in the direction of the arrow I (Fig. 2), by a reversing gear which is constituted for instance by the bevel wheels 4. The worm 3 engages with a worm

wheel 6 which is mounted on the horizontal measuring spindle 5 and rigidly secured to a driving wheel 7 provided with lateral teeth. To the latter wheel can be temporarily coupled a laterally adjustable toothed disc or 55 arm 8 which is also provided with teeth at one side for engagement with the wheel 7 and secured to the sleeve 9. On the said sleeve is further arranged a toothed wheel 10 provided with lateral ratchet teeth 10a and 60 meshing with a wide toothed wheel 11. The latter is mounted on the spindle 13 supported in the bracket 12 and is rotated by a spring 14 in such a manner that it is pressed with one of the pins 15 provided on it, against a 65 fixed stop 16. The disc 8, the sleeve 9 and the wheel 10, form the so-called measuring part and are jointly designated by M.

The sleeve 9 is provided with an annular groove 17 with which engages a control lever 18 pivotally arranged on a spindle 40, and is mounted on the measuring spindle 5 in a rotatable and laterally adjustable manner. A pin 19 provided on the wheel 10 co-operates with the pin 20 of a toothed wheel 21 provided with lateral ratchet teeth 21a, the said wheel 21 being rotatable with its hub 22 on the measuring spindle 5, but prevented from moving in the lateral direction. (For the sake of simplicity the pins 19 and 20 have not been shown in Fig. 2.) The toothed wheel 21 meshes with a toothed wheel 23 which is also mounted on the spindle 13 and rotated by a spring 24 in the direction like the wheel 11, that is, until a pin (not shown) on the same strikes a fixed stop. A toothed wheel 27 is further secured to or made integral with the hub 22 which wheel meshes with a toothed rack 28 which operates the recording device which will be described in detail later on. 70 To the hub 22 is further secured a bevel wheel 29 which drives through the bevel wheel 30 the spindle 31 of the pointer 32. The parts 21, 22, 27, 29 form together the 75 so-called setting part and are jointly designated by E.

A toothed wheel 34, which is rotated from the driving spindle 2 drives through the intermediate wheel 35 a toothed wheel 36 which is mounted on the so-called time spindle 37, 100

the uniform movement of which is regulated by a known anchor escapement not shown here. To the lower end of the time spindle is secured the control disc 38 which carries 5 cams or bosses with two steps 39¹, 39² of different heights. On the horizontal spindle 40 of the control lever 18 is rotatably mounted a sleeve 41 which carries a downward arm 42 which is constantly pulled by 10 a spring 43 against the control disc 38. The arms 18 and 42 form together the so-called control lever.

Locking pawls 44 and 45 engage with the lateral ratchet teeth of the toothed wheels 15 10 and 21 respectively which pawls are connected together by an intermediate rod 46 and pulled by the spring 47 to the left so that in the position of rest the intermediate rod 46 allows only the pawl 45 to press against 20 the ratchet teeth 21a of the toothed wheel 21, whilst the pawl 44 remains disengaged. This pawl is controlled by the adjustable toothed wheel 10.

The working of the arrangement is as follows:

The driving spindle 2 drives the worm 3 through the reversing gear always in one direction (arrow I) and the worm wheel 6 is rotated correspondingly. The driving spindle 30 2 always winds the clockwork spring, owing to which the time spindle 37 is rotated in the direction of the arrow II in Figure 2. By means of an anchor escapement not shown in the drawings, the time spindle 37 is given a 35 uniform rotation, that is, it makes for instance six revolutions per minute.

The spring 43 pulls the arm 42 of the control lever towards the control disc 38, at the same time the driving wheel 7 and the toothed 40 disc 8 are in mesh, so that the toothed wheel 10 is also rotated at the same time. By means of the pins 19 and 20, the toothed wheel 21 is also driven, owing to which the pointer 32 is deflected at the same time in accordance 45 with the speed at the moment. When one of the cams or projections of the control disc 38 arrives opposite the arm 42, the latter will be forced back by the foremost and highest step 39¹, and the coupling between the wheel 50 7 and the measuring part M will be disconnected, at the same time the toothed wheel 10 will be held fast in its position by the locking pawl 44.

The toothed wheel 10 will be forced however to the right to such an extent that the pawl 44 will push away the other pawl 45 by means of the intermediate rod 46 to such an extent that the toothed wheel 21 will be released. The return of the wheel 21 is, however, rendered impossible in that its stop 20 bears against the stop 19 of the locked wheel 10. Owing to the movement of the measuring part M, the pawl 44 has been brought therefore into engagement with the lateral ratchet teeth 10a, so that during the setting

of the pointer, the measuring part is held fast. When now the second lower step 39² comes into engagement with the lever 42, the lever will push the measuring part M slightly to the left, without however the latter coming into engagement with the driving wheel 7. During that time the toothed wheel 21 will be locked again by the pawl 45 and in that way the pointer fixed. In this position of the lever, the measuring part will be 75 released by the pawl 44, so that owing to the rotation by the toothed wheel 11, it will be turned back until the toothed wheel 11 reaches with its pin 15 the stop 16. The measuring part is now back again in its initial position. The cam step 39² passes then beyond the lever arm 42, so that the latter will be completely released, whereupon the measuring part will be again coupled to the driving wheel 7, and the measuring will be 80 repeated.

The single stepwise advance movements always take place between two escapement impulses i. e. the lever controlled by cams must drop from the cam intermittently between every two escapement impulses whereby the advance movements take place instantaneously and the single periods, such as the measuring time and the setting time, are 85 separated from one another in a very precise 90 manner.

It will be seen that the measuring part M drives the setting part E directly, that is, in such a manner that the pin 19 by its circular movement transmits the movement direct to the pin 20. The toothed wheels 11 and 23 of the device for re-setting enable the stops to be arranged not on the measuring part and setting part, but on the toothed wheels 11 and 23, owing to which the measuring part and the setting part are protected from hard shocks, and these parts are not acted upon by the re-setting springs 14 and 24 during the standstill of the vehicle. In that way the apparatus runs more easily during the standstill, and the wear is therefore much smaller.

On the driving spindle 2 an eccentric disc 48 is located, which operates a rod 49 the fork shaped end of which is equipped with 115 pawls 50. These pawls engage a ratchet wheel 52, which is fixed to the winding spindle 51, whereby the ratchet wheel is always rotated in the direction of the arrow III (Fig. 2).

On the winding spindle 51 are mounted one above another spring boxes or barrels 55 (Fig. 3) in which the winding springs 56 are secured by means of hooks 57 to the casing of the barrels and by means of hooks 58 to the hub of the next barrel. These mainsprings are thereby connected together in series in the known manner in order to obtain the greatest possible length of spring and a long 120 running down time.

The ratchet wheel 52 is integral with the driving wheel 59 and is rigidly secured to the winding spindle 51. With the teeth of the driving wheel 59 engages the driving pawl 60 (Fig. 4) which is rotatably mounted on the pin 62 secured to the bottom 61 of the lowermost spring barrel. This bottom has the form of a brake wheel and is equipped with ratchet teeth. A pawl 63 (Fig. 2) prevents a rotation to the right. When therefore the driving wheel 59 is turned in the direction of the arrow III, this rotation is transmitted through the driving pawl 60 and pin 62 to the bottom or brake wheel 61 and to the hub 64 of the same and thereby successively to the single main springs. The uppermost barrel is rigidly secured to a toothed wheel 34 and drives as mentioned above by means of the countershaft constituted by the toothed wheels 35, 36, the so-called time spindle 37.

One of the spring barrels 55 is provided throughout the whole of its height with teeth 65, and the spring box above it, is provided at the top with a narrow toothed ring 66. In a sleeve 67 mounted on the casing A, and in a bracket 68 is mounted in an adjustable and rotatable manner the control spindle 69 to which is secured a wide toothed wheel 70 co-operating with the toothed wheel 65. The wheel 70 is connected to a fixed or loose cylindrical hub 71 extending downwards. Between the arms 72 of the bracket 68 is arranged a toothed wheel 73 which co-operates with the toothed wheel 66. The control spindle 69 is provided at the top with a left hand flat screwthread 74 on which is mounted the toothed wheel 73 formed into a nut.

The driving pawl 60 has a projection or arm 75 (Fig. 4) and to this arm a flat pressure spring 77 is fastened by means of rivets or screws 76. On the pin 62 a U-shaped protective cap 78 is pivotally arranged and the spring 77 presses this cap outward against a stop 80. A second spring 81 presses the driving pawl 60 against the driving wheel 59.

The winding spindle 51 may also be rotated by means of a hand wheel 82.

The working of the device is as follows:

When the clockwork is completely run down the single parts are in the positions shown in Figs. 2 and 4 and the driving wheel 59 is constantly rotated in the direction of the arrow III by the driving spindle 2 or by the hand wheel 82.

When a mainspring is fully wound for instance to the extent of six turns, the uppermost mainspring hub will make 6 revolutions, the second hub 12, the third hub 18, the fourth hub 24, the fifth 30, the sixth 36 and the lowermost 42 revolutions. It follows therefrom that during the full winding the toothed wheel 65 makes six revolutions more than the toothed wheel 66, and that the

toothed wheel 70 rotates to the right faster than the toothed wheel 73, so that the control spindle 69 will be lowered, that is to say, until the cylindrical hub 71 reaches the protective cap 78. This will now press the spring 77 against the arm 75 and simultaneously the driving pawl 60 will be disengaged whereby the winding operation ceases. The spring 77 being stronger than the spring 81, the driving pawl 60 will in the moment of disengagement be swung out until the teeth of the driving wheel 59 are completely released. The time spindle 37 will however continue to rotate so that the mainsprings 56 will gradually run down. The wheel 66 rotates during that time faster than the wheel 65, and the control spindle 69 with the hub 71 slightly rises so that the driving pawl 60 is released again, and the winding takes place again. This is possible, as the pawl 60 unhindered may pass the control spindle 69, because the releasing hub 71 now takes up a higher position than the pawl 60. When the driving spindle 2 is constantly rotating, the control spindle 69 regulates the spring tension between quite small limits and when the engine shaft stops, the mainsprings are allowed to run down until the wheel 70 in the bracket 68 has reached the bottom.

As mentioned above, the toothed wheel 34 of the uppermost spring barrel drives through the toothed wheels 35, 36 the time spindle 37. On the shaft of this gearing a worm 88 (Figures 1 and 2) is arranged which through a worm wheel 89, a spindle 84 and a toothed wheel 85 drives a toothed wheel 90, which makes one revolution every hour. With this wheel the hour wheel 91 is rigidly connected which also makes one revolution every hour. This wheel is formed with four raising cams of which the first three, 92 (Fig. 1) are identical, whereas the fourth cam 93 is somewhat steeper than the others. Each cam has an inclined end and is formed with 15 equal sharp teeth or cuts 94. The last tooth of each cam is connected with the first tooth of the next cam by means of an inclined face. On the said cams a lever or arm 96 slides, which is pivotally arranged on a pin 95. This arm 96 cooperates with the said cams by means of a tooth 97 and transmits its movements to the recording rod 99 by means of a projection 98. The hour wheel 91, which is driven from the clockwork, carries the minute hand 32. At the upper end of the recording rod 99 the recording pencil 102 is mounted, which records the time line 103 shown in Fig. 5 on the strip 108. The time line consists of a saw-teeth like line, the inclined lines 104 and 105 interrupting it representing any desired medium time unit. In the construction according to Figure 5, this interruption is effected at each quarter of an hour, namely in such a manner that the time line 103 rises in the first three quarters of an hour to the same

height, whilst in the last quarter of an hour this rise is strikingly steeper so that the end 104 of the last quarter of an hour can be easily noticed, especially as the ends 105 of 5 the intermediate quarters of an hour are lower. Every minute (small time unit) a small stroke 106 is made so that the single minutes can be easily distinguished on the time line. The minute strokes and the last 10 strokes of the single quarters of an hour represent the 15th, 30th and 45th minute of an hour. The last stroke, of the fourth quarter of an hour represents at the same time the moment of a full hour which is marked 107 15 in Figure 5. It is evident, that the first strokes represent the first minutes of each quarter of an hour, that is to say the 1st, 16th, 31st and 46th minute. It is therefore easy 20 to read in Figure 5 that a train arrived for instance at $(X-1)$ hours and 53 minutes, left 5 minutes afterwards and arrived at the next station at X h.8 minutes and continued its journey after two minutes.

This method of time recording has the 25 great advantage that the time recording in full hours (large time unit) quarters of an hour (medium time unit) and minutes (small time unit) is very clear, and that one simply reads from left to right the minutes, owing 30 to which the strip may be made of a considerably smaller width than in the construction hitherto known.

It will be readily understood that the pencil 102 at the end of each quarter of an hour 35 will draw the inclined lines 104, 105, that the time line 103 rises gradually during each quarter of an hour, whereby the last quarter of an hour will be drawn higher and that each minute there will be produced a vertical minute stroke 106. The recording strip 108 may 40 of course be moved according to time also during the trip or journey. In order that also the direction of driving may be recorded on the recording strip the speedometer according 45 to the invention is equipped with a special device which will now be described.

In order that the direction of travel, that is to say, the forward or backward travel of the vehicle, may be recorded on the recording strip 108, the following system is provided:

The recording strip 108 is guided over a plate 109 shown in Figure 7. A pencil 83, which is mounted on an arm 110 of a rod 134 55 produces on the strip 108 a thin straight line during the forward travel of the vehicle and a thick straight line when the vehicle is travelling backwards. The rod 134, whose drive is hereinafter described, is prevented from rotation in that an arm 112 (Figs. 6 and 7) secured to the rod 134 engages a rod 113. A pressure spring 114 (Fig. 6) presses the recording rod 134 downward to an extent permitted by the sleeve 115. A sleeve 119 (Figs. 6 and 9) which carries an arm 120 is rotatably 60 65

mounted on the cross spindle 40. To the said arm is secured at the top a rod-like arm part 121 and at the bottom a flat spring 122 (Fig. 8). The bevel gears 4 of the sleeve 1 70 cooperate with claws 125, 126 guided by pins 123, 124 and the arm part 121 and the flat spring 122 project between the said claws and force them apart. It will be clearly seen from the drawing that during the forward travel (direction of the arrow I of Fig. 9) the 75 claw 126 directly drives the upper bevel wheel, that is to say, it merely rotates it while the rotating claw 125 runs idly in that it slides over the teeth of the lower wheel 4 and moves up and down. The axial movements 80 of the claw 125 are also transmitted to the tension spring 122 whilst the arm part 121 remains at rest. To the sleeve 119 is secured a second arm 127 which is connected by a pin 128 to a lifting rod 129 for the recording rod 134 extending through the sleeve 115. During 85 the forward travel, the pencil 83 remains stationary and writes on the strip 108 a thin straight line indicating the forward travel. When the vehicle is travelling backwards, the 90 claw 125 will drive the lower bevel wheel 4 and the sleeve 1 over the two other bevel wheels and make only a rotary movement while the claw 126 makes a reciprocatory movement. This movement is transmitted 95 by the arm part 121 through the parts 120, 119, 127, 128, 134, 110 to the pencil 83 thereby 100 producing a thick line which indicates the backward travel and can be easily distinguished. The thickness of this thick line depends on the play 132 (Fig. 6) between the 105 sleeve 119 and the rod 134. This play may also be provided, for instance, between the lifting rod 129 and the arm 127.

The device produces on the recording strip 108 a speed curve by means of a pencil 135, a time curve by means of the pencil 102 and a straight line for the direction of travel by means of the pencil 83. The time is also indicated by the minute pointer 32.

Having now particularly described and ascertained the nature of the said invention, and in what manner the same is to be performed, I declare that what I claim is:

1. In a speedometer with positive drive, a measuring device adapted to rotate intermittently and then return to the initial position, a setting device including an axially displaceable wheel, a single joint control lever for throwing said measuring device in and out of gear and for releasing and locking said setting device and means for operating said control lever.

2. In a speedometer with positive drive, a measuring device adapted to rotate intermittently and then return to the initial position, a setting device, a single joint control lever for throwing said measuring device in and out of gear and for releasing and locking said setting device means for operating

said control lever and other interconnected means for locking the measuring device during the setting of the setting device and vice versa.

5. 3. In a speedometer with positive drive, a measuring device adapted to rotate intermittently and then return to the initial position, a setting device, a single joint control lever for throwing said measuring device in and out of gear and for releasing and locking said setting device, means for operating said control lever, other interconnected means for locking the measuring device during the setting of the setting device and vice versa and 10 still other means for automatically bringing said measuring and setting devices back to initial position after each period of activity.

4. In a speedometer with positive drive, a measuring device adapted to rotate intermittently and then return to the initial position, a setting device, a single joint control lever for throwing said measuring device in and out of gear and for releasing and locking said setting device, a control disc with steps 20 for bringing the control lever into different positions for the purpose of obtaining different effects, two locking pawls of the measuring device and the setting device being so interconnected, that during the period of the greatest deflection of the measuring device 25 the second pawl is held disengaged by the first pawl, in order to enable the setting of the setting device.

5. In a speedometer with positive drive,

35

40

45

50

55

60

65

a measuring device adapted to rotate intermittently and then return to the initial position, a setting device, a single joint control lever for throwing said measuring device in and out of gear and for releasing and locking said setting device, a control disc with steps for bringing the control lever into different positions for the purpose of obtaining different effects, two locking pawls of the measuring device and the setting device being so interconnected, that during the period of the greatest deflection of the measuring device the second pawl is held disengaged by the first pawl, in order to enable the setting of the setting device, and the measuring device is engaged by the first pawl during the setting operation and spring controlled means for automatically bringing said measuring and setting devices back to initial position after each period of activity.

6. In a speedometer with positive drive, a direction indicating marker, a drive shaft, two sleeves slidable on said shaft, and means for transmitting sliding movement of said sleeves to said marker, said movement transmitting means including a rigid member and a spring pressing said member against one of said sleeves.

7. A speedometer as claimed in claim 6, characterized in that said rigid member and spring constitute a fork.

In testimony whereof I affix my signature.

KOLOMAN REZSNY.
